UNITED STATES PATENT OFFICE

2,665,462

ROLL-OVER FOUNDRY MACHINE

Lester C. Young, Cleveland, Ohio, assignor to
Spo, Inc., a corporation of Ohio

Application July 19, 1949, Serial No. 105,555

4 Claims. (CL. 22—32)

1

This invention relates to foundry machines in general, and relates more particularly to jolt roll-over machines.

An object of this invention is to provide a power device adapted to disturb the balance of a jolt roll-over machine.

Another object of this invention is to provide power brake means to arrest rotation and swing of a jolt roll-over machine.

A further object of this invention is to provide a remotely controlled pulsation power device to disturb the balance of a roll-over machine, and an automatic brake device to stop rotation and swing of the machine in a predetermined position.

A further object of this invention is to provide an improved brake structure.

A still further object of this invention is to provide an improved control system for selective manual or automatic operation of a brake.

Yet another object of this invention is to provide an improved interconnection between a jolt machine and a brake therefor, adapted to transmit braking torque and prevent transmission of vibration.

Other objects and a fuller understanding of the invention may be had by referring to the following description and claims, taken in conjunction with the accompanying drawings in which:

Figure 1 is a type of foundry machine employing the improved principles of this invention;

Figure 2 is a longitudinal section through the right-hand trunnion and brake device of the machine as viewed in Figure 1;

Figure 3 is an end view of the right-hand trunnion and brake;

Figure 4 is a broken section along line 4—4 of Figure 2, showing the vibration-resisting device for transmitting braking torque from the brake to the trunnion of the machine;

Figure 5 is a front elevational view of the left-hand trunnion and the power unbalancing device;

Figure 6 is a side elevational view of the left-hand trunnion and the power unbalancing device;

Figure 7 is a schematic layout of the power unbalancer and brake devices, with the accompanying fluid lines and controls set to unbalance the machine and thereafter automatically stop rotation and swing of the foundry machine in a predetermined position;

Figure 8 illustrates the operation of the control system to actuate the automatic brake;

2

Figure 9 illustrates the operation of the control system to release the brake; and

Figure 10 illustrates the operation of the control system by manual operation.

With reference to the drawings, Figure 1 illustrates a type of foundry machine which may be adapted to employ the principles of this invention. In the Figure 1, the reference character 10 designates a stationary base having a support member 11 and a support member 12. A work unit 13 is provided with trunnions 14 and 15 as best illustrated in the Figures 2 and 6, and the trunnions 14 and 15 are suitably bearinged to support the work unit 13 upon the support members 11 and 12.

The work unit 13 may be any suitable foundry machine employed for the purpose of jolting a sand mold to compact the sand about a pattern. In addition to the normal jolting operation, such machines as the work unit 13 are also employed to squeeze the sand mold and perform other similar operations. The illustrated work unit 13 is provided with a table 16 upon which the mold preparation work is carried out.

Some mold preparation operations may be carried out upon stationary floor-mounted jolt machines, but in other instances after the sand has been compacted upon a suitable pattern, it is necessary to turn the mold upside down. This operation has been carried on for some period of time in ordinary foundry practice, and is normally accomplished in a machine similar to that illustrated in the Figure 1 of the drawings, but lacking the features hereafter to be described.

In foundry practice, a pattern and the sand are placed within a confining flask and jolted to compact the sand by raising the table 16 a short distance and allowing the table with the load thereon to drop against a solid stop member. The work unit 13 has suitable fluid-operated piston and cylinder jolt apparatus to jolt the table 16 and its load. Also, the work unit 13 has suitable piston and cylinder means to move the table 16 continuously toward two hook arms 21. Thus, the table 16 and the hook arms 21 can grip the mold and hold it against dislodgment from the work unit 13.

When the foundry machine illustrated in Figure 1 is not in operation, as illustrated in the Figure 1, the lower portion of the work unit 13 below the table 16 is considerably heavier than the hook arms 21, and therefore the center of gravity is below the trunnions 14 and 15 and the work unit 13 will rest in the position illustrated. However, the weight of the work unit 13 and the length of the hook arms 21 is so proportioned

that when a sand-filled flask is moved by the table 16 up against the hook arm 21, the center of gravity of the work unit 13 will shift above the trunnions 14 and 15. Shifting of the center of gravity above the trunnions would be expected to start the work unit 13 rotating, but because the table and load are moved directly upward, the work unit 13 very often will not be started to rotate upon the support members 11 and 12 without an external force being applied. That is, the normal friction upon the support members 11 and 12 is not overcome by the very slight leverage which might be created by reason of the shifting of the center of gravity above the trunnions 14 and 15.

In the embodiment of the invention illustrated, a rotation starter 22 is provided to throw the work unit 13 out of its normal balance after the load and table have been moved upwardly, and thereby start the work unit rotating upon the support members 11 and 12.

The rotation starter 22 includes a cylinder 23 and a piston 24 pivotally secured to the support member 12 by means of pivot 28. The piston 24 is provided with a piston rod 26, and the end of the trunnion 15 is provided with an eccentric 25. The piston rod 26 is connected to the eccentric 25 and is thereby adapted to give a short rotational impulse to the trunnion 15 when the piston 24 is moved forward in the cylinder 23. A suitable fluid line 27 is adapted to supply fluid under pressure to the piston 23, and therefore when the operator desires to start the work unit 13 rotating, fluid is supplied through the line 27 and a short impulse is provided to throw the work unit 13 off of its normal stable position and begin a roll-over movement of the work unit 13.

Figure 2 of the drawing illustrates the preferred embodiment of a brake device of this invention. In the Figure 2, the trunnion 14 is bearinged upon the support member 11 by means of suitable bearing material 31, and is held in position by the bearing cap 30. Pin 32 is provided to hold the bearing insert and assure relative movement between bearing surfaces, rather than between the bearing material and the cap 30.

Brake body 33 is nonrotatively mounted upon the support member 11 and held in proper alignment relative to the support member 11 by means of dowel pins 29. Brake plunger 35 is reciprocably carried by the pilot ring 36 on the brake body 33, but is prevented from rotating by means of plunger guide pins 37 in the pilot ring 36. A diaphragm 38 is securely held over the brake plunger 35 by a diaphragm cover 39. The diaphragm and the diaphragm cover 39 thereby provide an extendable fluid chamber 17. Fluid is introduced into the fluid chamber 17 through the fluid line 40, and will force the plunger 35 inwardly.

A brake key 41 is secured to the trunnion 14, and therefore will revolve with the trunnion 14. A brake disc holder 42 is provided with a longitudinal slot 44 substantially as illustrated in the Figure 4 of the drawing, and is positioned by the brake body 33 to extend substantially coaxial with the axis of the trunnion 14. A brake disc 43 is secured to the brake disc holder 42 and extends from the holder 42 between mating surfaces of the brake body 33 and the plunger 35. Brake linings 18 are riveted, or otherwise secured to the surfaces of the brake disc 43. The

linings 18 provide a high coefficient of friction for efficient brake action.

The preferred embodiment of the brake device illustrated in Figure 2 has two general working parts, namely, the nonrotative parts which comprise generally the stationary parts 33, 39 and 35 and the rotating parts which comprise generally the trunnion 14, the key 41, and the brake disc holder 42. The nonrotative parts and the rotating parts are adapted to be interconnected by a brake to arrest the rotational movement of the work unit 13. Further, the rotating parts of the brake device are connected to the work unit 13 for torque braking transmission, but are provided for shiftable interconnection through the key 41 and the transfer slot 44 to prevent the transmission of jolting shocks from the work unit 13 to the clamped surfaces of the brake.

The stationary, or nonrotative portions of the brake comprise the brake body 33 secured to the support member 11, the diaphragm cover 39, and the reciprocable but nonrotative brake plunger 35.

The rotational portion of the brake comprises generally the brake disc holder 42 with the brake disc 43 thereof extending between mating surfaces of stationary members 33 and 35. A longitudinal slot 44 in the brake disc holder 42, and a cooperating brake key 41 carried by the trunnion 14, together provide for torque transmission but prevent vibration transmission. The key 41 and slot 44 are extended vertically when the work unit 13 is in the position illustrated in Figure 1 in order that the normally vertical vibration will not be transmitted.

In operation, either by manual control or automatic control, after the table 16 is lifted to squeeze a load against the hook arm 21, fluid is directed into the rotation starter 22 and a rotational impulse is given to the work unit 13. No more energy need be supplied than a mere impulse, because once thrown off of the normally balanced position, the work unit with the load raised against the hook arms 21 will begin to rotate to place the center of gravity thereof below the trunnion members 14 and 15. Thereafter, the rotation starter 22 is carried along by the work unit 13. Once started to rotate, the work unit 13 may be stopped in any selected position by the brake device.

Figures 7, 8, 9 and 10 illustrate the fluid supply control to the rotation starter 22 and to the brake device. In Figure 1 of the drawings, distributing valves 50, 51, 52 and 53 are mounted on the support member 11. Distributing valves 52 and 53 are provided to control the jolting and squeezing action of the table 16, and therefore have no bearing upon the present invention. The valves 50 and 51, however, are employed to control the flow of fluid and exhaust from the rotation starter 22 and the brake.

The actual physical construction of the valves 50 and 51 may be of any suitable type having multiple positions of flow through the valve, and the illustrated embodiment employs a four-way valve. That is, the valves are adapted to direct fluid from a supply line 58 into selected lines directed to the machinery, or to exhaust as desired.

In the Figures 7-10, the entire control system is set forth diagrammatically, and the lines charged with operating fluid under pressure being illustrated in heavy dimension, and the lines which are inoperative being illustrated in light dimension. In Figure 9, the lines 40, 55 and 57 are being exhausted, and are therefore illustrated

in broken heavy dimension. In Figure 7, the handles of the distributing valves 50 and 51 are in the lower position. In that position, fluid under pressure will be directed from the supply line 58 through the valve 51 and fluid line 27 into the rotation starter 22. As illustrated, fluid under pressure is directed from the supply line 58 through the valve 50 into line 62 leading to a cam operated valve 45, and to a supply line 56 leading to a valve 60 having pressure operated control bellows. The valve 60 is situated in fluid line 55 leading from the valve 51 to the brake line 40, and therefore may be actuated to open and close line 55. A fluid line 57 leads from the cam operated valve 45 to the fluid line 40 of the brake. A check valve 59 is situated in the line 62 and is adapted to prevent the flow of fluid from the cam operated valve 45 back into the valve 59. Fluid under pressure is not obstructed from flowing from the valve 50 into the valve 45, however. Therefore, as illustrated in the Figure 7, the starter 22 is actuated and will begin operation to give a starting impulse to the work unit 13, but the brake is inoperative.

Referring now to the Figures 1 and 2 of the drawings, the cam operated valve 45 is illustrated as being stationarily mounted on top of the bearing cap 30. A cam 46 is carried by the work unit 13, and therefore when the cam 46 contacts the plunger of the valve 45, the valve 45 will allow the fluid to pass from the line 59 into the lines 57 and 40 to fill the fluid chamber 17 and actuate the plunger 35 to thereby grip the brake disc 43. The cam 46 is illustrated as being a small cam adapted to actuate the valve 45 at one particular time and thereby throw full braking action onto the plunger 35, but it is to be understood that a longer cam track, even to the extent of a completely circular cam track, may be provided around the trunnion 14 to allow fluid under pressure to pass in various controlled amounts to the valve 45 and thereby apply the braking action to any selected degree at any relative position of the work unit 13 with respect to the base 10. Or other cams, such, for example, as cam 146 (see Figure 2), may be placed in spaced relationship to provide predetermined positions of braking.

When the cam operated valve 45 is actuated by contact with a cam, the condition of operation is substantially as shown in the Figure 8. The operator of the machine, after having actuated the valve 51 to give a rotational impulse to the starter 22, will return the handle of the valve 51 to the neutral position illustrated allowing the fluid in line 27 to be exhausted to atmosphere through exhaust port 61. Therefore, in the Figure 8 the line 27 appears in small dimensions indicating that the line 27 is inactive after the handle of the valve 51 is returned to a neutral position. Once the valve 45 is actuated by the cam 46 to permit fluid under pressure to pass therethrough into the brake line 40 as illustrated in Figure 8, the fluid fills the lines 57 and 40 to actuate the brake, and also backs up along the line 55 to the valve 60. However, the valve 60 is adapted to close the line 55 when pressure is exerted upon the valve 60 through the fluid pressure line 56. Therefore, the fluid under pressure cannot escape from the brake through the valve 60 as long as the handle of valve 50 is in the position to allow fluid under pressure to fill the line 56. Consequently, the full force of the fluid under pressure is exerted upon the brake, and the rotational and swinging movement of the work unit 13 is brought to a halt

and is held there indefinitely until the operator desires to release it.

Release of the automatic brake is effected by the operator by raising the handle of the valve 50 to the neutral position as indicated in Figure 9 of the drawing. The neutral position allows all fluid under pressure to escape from the valve 50 and shuts off the supply line 58 from the valve 50. Release of the fluid pressure from the line 62 will not permit the fluid to escape backwards through the line 62 from the valve 45 because of the check valve 59, but when the handle 50 is placed in neutral position to exhaust the fluid to atmosphere the line 56 is also exhausted to atmospheric pressure and the valve 60 is then permitted to pass the fluid from the line 40 through the line 55 and out through the valve 51 to the atmosphere.

The brake may also be operated manually by use of the valve 51. For manual operation, as illustrated in Figure 10, the handle of the valve 51 is actuated upwardly to supply air to the line 55. The valve 50 is allowed to remain on the neutral exhaust position. Thus, the valve 60 is open and will allow the passage of fluid therethrough and the line 55 will supply fluid under pressure directly to the brake. Since the line 57 is coupled into the line 40 along with the line 55, the fluid under pressure from the line 55 will attempt to escape through the valve 45 and the valve 50 to atmosphere. The check valve 59 will prevent such an escape of the pressure, however, and hold the fluid to actuate the brake device. After manual operation, the handle of the valve 51 is merely pushed down to the neutral position as illustrated in Figure 9, and the pressure is released from the brake.

In operation, the mold flask is placed upon the table 16 when the machine is in the position illustrated in Figure 1. The valves 52 and 53 are thereafter operated to successively jolt sand in the flask until it is compacted to the desired degree, and then actuated to force the table 16 upwardly towards the hook arm 21 and squeeze and clamp the flask therebetween. As previously explained, such an upward shifting of the table 16 and the load carried thereon will place the center of gravity above the trunnions 14 and 15. The operator momentarily flicks the handle of the valve 51 down as illustrated in Figure 7, and the starter 22 is thereby given an impulse to start rotation of the work unit 13 by throwing the work unit 13 out of balance as previously described. Then the operator pushes the handle of valve 45. Immediately thereafter the handle of the valve 51 is placed in the neutral position, and the handle of the valve 50 is allowed to remain in the down position which places a potential charge upon the brake 40, but the potential charge is held away from the brake by the valve 45.

After the work unit 13 is unbalanced it will begin to rotate in an attempt to place the center of gravity below the trunnions 14 and 15. Of course, once the rotation has started the natural momentum of the work unit 13 will attempt to carry the hook arm 21 beyond an exact inverted position from that illustrated in the Figure 1. This excessive rotation may be stopped either automatically by the provision of a suitable cam to open the valve 45 at a predetermined position, or may be stopped by manual operation as described in conjunction with the Figure 10.

Furthermore, after the squeeze has been released and the table 16 pulled up, the center of

gravity will again be above the trunnions 14 and 15. Once again the starter 22 may be employed to begin the return rotational movement. This return rotational movement may then be arrested by actuation of the valve 45 by means of the cams, or by manually braking, as previously described.

Although the invention has been described in its preferred form with a certain degree of particularity, it is understood that the present disclosure of the preferred form has been made only by way of example and that numerous changes in the details of construction and the combination and arrangement of parts may be resorted to without departing from the spirit and the scope of the invention as hereinafter claimed.

What is claimed is:

1. In a roll-over machine having a base member and a work unit bearinged on said base member for rotational and swinging movement, the provision of power controls for initiating and stopping movement of the work unit comprising, rotation starter means having a fluid operated piston and cylinder and crank arm drivingly interconnecting said base member and work unit, said rotation starter means having a limited power period sufficient only to start rotation of said work unit, whereafter the work unit is released to rotate freely by gravity, a fluid pressure line connected to supply fluid under pressure to said cylinder, valve means in said fluid pressure line having a first position to direct fluid under pressure into said fluid pressure line, and a second position to exhaust said cylinder, brake means to momentarily arrest rotational and swinging movement of said work unit, said brake means having fluid power actuation means, a fluid pressure line connected to supply fluid under pressure to said fluid power actuation means, a control valve in said fluid line to the brake, said control valve having an actuator adapted to be operated by contact with a cam control, and a cam control member to operate said control valve, said control valve and cam control being mounted to move relative to one another corresponding to the relative movement of the work unit and base to thereby operate the control valve and brake to arrest the movement of the work unit at any selected position.

2. Brake means for a jolt roll-over machine having a base member and a jolt work unit bearinged on said base member comprising, a brake unit secured to said base member having a rotatable member, a clamp member, and means to clamp said clamp member on said rotatable member and lock said rotatable member, and torque transmission means interconnecting said rotatable member and said work unit, said torque transmission means including a longitudinal tongue-and-groove union to permit axial shifting of the work unit with respect to the brake means and transmit rotational torque.

3. In a roll-over machine having a base mem-

ber and a work unit bearinged on said base member for rotational and swinging movement, the provision of power controls for initiating and stopping movement of the work unit comprising, rotation starter means drivingly interconnecting said base member and work unit, said rotation starter means having a limited power period sufficient only to start rotation of said work unit whereafter the work unit is released to rotate freely by gravity, a power transmission line connected to supply power to said rotation starter means, control means in said power transmission line having a first position to momentarily direct power to said rotation starter means, and a second position to release said rotation starter means from all driving and retarding forces in order that the work unit may rotate freely by gravity, and brake means separate from said rotation starter means to arrest rotational and swinging movement of said work unit at any selected position.

4. In a roll-over machine having a base member and a work unit bearinged on said base member for rotational and swinging movement, the provision of power controls for initiating and stopping movement of the work unit comprising, rotation starter means drivingly interconnecting said base member and work unit, said rotation starter means having a limited power period sufficient only to start rotation of said work unit whereafter the work unit is released to rotate freely by gravity, a power transmission line connected to supply power to said rotation starter means, control means in said power transmission line having a first position to momentarily direct power to said rotation starter means, and a second position to release said rotation starter means from all driving and retarding forces in order that the work unit may rotate freely by gravity, brake means separate from said rotation starter means to arrest rotational and swinging movement of said work unit at any selected position, and means to coordinate operation of said rotation starter means to initiate operation of said starter means first and said brake means thereafter.
